UNITED STATES PATENT OFFICE.

LEE A. MEDCALF, OF FAIRGROVE, MICHIGAN.

BEAN-SORTING DEVICE.

Application filed April 18, 1922. Serial No. 554,566.

To all whom it may concern:

Be it known that I, LEE A. MEDCALF, a citizen of the United States of America, and a resident of Fairgrove, in the county of Tuscola and State of Michigan, have invented certain new and useful Improvements in Bean-Sorting Devices, of which the following is a specification.

This invention relates to bean sorting devices and the like, and particularly to a device for sorting the beans into their respective grades before being taken to the elevators or otherwise disposed of.

One object of the invention is to provide a simple and inexpensive machine which will sort and separate the beans into four or more distinct and separate grades.

Another object of the invention is to design a machine equipped with scrapers and brushes for agitating and rolling the beans fed onto the sorting table, to the end that the different grades will be diverted and roll into the proper channels and be scraped into separate spouts or pockets.

A further object is to design a small and compact sorting machine which can be utilized and operated by each individual bean grower as well as by the bean elevators, and which can be constructed in units to increase the machine to any desired capacity.

With the above and other objects in view, the present invention consists in the combination and arrangement of parts, hereinafter more fully described, illustrated in the accompanying drawings and particularly pointed out in the appended claims, it being understood that changes may be made in the form, size, proportion and minor details of construction without departing from the spirit or sacrificing any of the advantages of the invention.

In the drawings:—

Fig. 1 is a top plan view of my improved sorting machine.

Fig. 2 is a vertical cross sectional view thereof taken on the line 2—2 of Fig. 1.

Fig. 3 is an enlarged fragmentary view illustrating the small rolling paddles in two different positions.

Fig. 4 is an enlarged fragmentary isometric view of one of the wire brushes.

Fig. 5 is also an enlarged fragmentary isometric view of one of the scrapers.

Fig. 6 is a fragmentary sectional view of the sorting table illustrating the dust, dirt and sand openings.

Fig. 7 is a similar alternate view illustrating the sorting table provided with a rubber top.

Fig. 8 is a view to illustrate that these sorting tables can be superimposed one above the other and thereby increase the machine capacity as desired.

Well developed perfectly formed beans when ripe and harvested are of a rounded slightly oblong shape, and will readily roll on a flat table if gently agitated, or if the table is tilted, and bean elevators are usually established in or near each bean growing district, these elevators purchase the crop from the grower, and are equipped with screens over which the beans are fed when purchased and the grower is paid for the screened beans, the cracked (or half beans) and undersized beans are termed the screenings, and these are not returned to the grower, nor is he paid therefor. In all elevators a considerable quantity of good beans screen into these screenings together with irregular shaped, undersized and cracked beans. Irregular shaped beans may be caused by blight or general adverse weather conditions, but are of the same food value as the perfectly shaped beans, and further, the cracked beans are exactly as good and nutritious, but the fact that they are split in half detracts from the commercial value thereof. They can however be sold as cracked beans and bring a fair price, and I have therefore designed a machine which will closely pick and sort the beans into different grades and thereby eliminate the screening. These machines can be owned and used by the grower or can be installed in the elevators at any desired capacity.

Referring now particularly to the drawings, in which I have shown the preferred embodiment of my invention, the machine comprises a round flat table 1 which is supported on the member 2, which is hollow as shown, the flange 2^a being rigidly secured to the underside of the table, this hollow member is suitably connected to the hollow vertically disposed shaft 3 which is journaled in the end as shown, this bearing being

spaced from the floor line and is supported by means of stays or braces 5 and 6 secured to the bearing and anchored to the floor, a friction member 7 is mounted on this vertically disposed shaft 3 intermediate its length, and is adapted to be rotated by means of a beveled friction 8 mounted on the transversely disposed shaft 9 which is journaled in suitable bearings and connected to a suitable source of power (not shown), and this vertical shaft 3 is set at a slight angle in order that the beans will roll thereon when the table is rotated.

The top of this sorting table is preferably flat and can be made up of wood, sheet metal or a thin casting and can be covered with rubber as shown in Fig. 7 of the drawings if desired. An opening 10 is formed in the center of the table as shown, and for a purpose to be presently described, a plurality of small openings 11 being formed around the outer edge of the table through which dust and fine particles of sand and dirt are adapted to sift as the beans are being fed onto the table.

The beans are placed in a hopper 12 suitably supported above and adjacent the table, the spout 13 thereof being in close proximity to the top thereof, the beans discharging through the spout and onto the table as it revolves. I also wish to direct particular attention to the fact that the table is inclined as clearly shown in Figs. 2 and 8, and this spout is located at approximately the top or high side thereof.

The hopper is preferably located directly above the small openings in the outer edge of the table, and is provided with a slide gate 14 to regulate the flow of beans therefrom, and as the beans discharge the dust, dirt and sand will fall through the openings 11 in the table. A wire brush 15 is positioned at an angle across the top of the table on the high side, a scraper blade 16 lying adjacent thereto and being spaced therefrom, the ends of the wires 17 riding on the surface of the table as does also the scraper 16. A short scraper blade 18 is positioned at right angles to these members 15 and 16 and is adapted to be secured to a scraper 19 which is spaced from the brush 15, and these scrapers and the brush are adapted to be secured together by means of stays or braces 20 and 21, secured thereto by the use of screws or the like. A metal band 22 partially surrounds the opening in the center of the table, the one end thereof being secured to the end of the scraper member 19, the opposite end being connected to the brush 23 which extends from the center to the outer edge of the table on the low side and at an angle to the member 19, a lip 22 also projecting outwardly as shown, a scraper member 24 lies adjacent the brush 23 and is spaced therefrom, and these two members are secured together by

means of the stays or braces 25 and 26, the member 21 also bridging these members and being secured thereto as shown.

A similar scraper 27 lies at an angle to the scraper 24 on the low side of the table, the inner ends of these two members being secured together and braced by the stay 21. A stay 28 is also secured to the outer end of this member 27 and the ends of this stay project beyond the table and are anchored in any suitable manner, the one end thereof being provided with a series of openings 29 adapted to receive a dowel pin 30 for securing the stay to the member 27 and to provide for the changing and adjusting of the brushes and scraper blades on the table, consequently it will be obvious that all of these scrapers and brushes are secured together.

A V-shaped member 31 is provided at the edge of the table between the members 23 and 24, the apex being secured to the cross brace 26, and the ends can be anchored beyond the edge of the table if desired, and this member serves to separate the beans which discharge from the table between the members 23 and 24 into two separate grades.

A plurality of small paddles 32 are pivotally mounted in the member 33 which is positioned adjacent to and spaced from the scraper 19, links 34 being mounted on the upper end thereof, the outer ends of these links are pivotally connected to a shifting member 35 for simultaneously adjusting these paddles to any desired angle, and these paddles serve to roll and divert the beans inwardly towards the discharge opening in the center as the table revolves, a rim 36 is secured to the members 19 and 23, and is positioned around the outer edge of the table, one end of a similar rim 37 being anchored to the member 27, the opposite end being anchored to a stationary stay and these rims prevent the product rolling from the table.

In practise the beans are introduced into the hopper member 12 which is located above the machine, the beans discharging through the spout 13 and flowing onto the revolving table which carries them around and against the stationary wire brush 16, these wires roll the product and the perfectly formed beans will roll down the passage way between the members 16 and 19 as indicated by the numerous arrows, this movement is due to the incline of the table and the revolving of the table which brings the product into contact with the wire brush, these beans strike the scraper blade 24 located on the low side of the table and which is also placed and pitched downward and outwardly with relation to the angle thereof. The product is then on the low side of the table and the rotation thereof tends to carry it up the incline and towards the high side, but if the bean is perfectly

formed it will roll outwardly and discharge into the spout or pocket 38, and if irregular in shape or flat, it will ride to the brush 23 which rolls it and causes it to again roll down the inclined table and against the scraper 24, and this is continuously repeated until it has worked to the outer edge of the table and is discharged on either side of the member 31 and into either of the 10 pockets 38 or 39. It will of course be understood that the beans discharging into the pocket 38 are the best #1 grade, the next grade being discharged into the pocket 39.

15 The revolving of the table has a tendency to carry the beans which have carried to the low side of the table upwardly and against the wire brush 23, with the exception of the product which passes through the wire 20 brush 16, and which consists of small stones, clods of earth, very rough beans and other foreign matter, this is forced down the passageway between the scraper 17 and the wire brush and takes the course as indicated by 25 the arrows, being discharged into the pocket 40, the rim 35 preventing it discharging and rolling off until forced off by the scraper blade 27. The culls, cracked beans and the like are carried up on the high side 30 in the direction of the rotation of the table and as indicated by the arrows the band 34 preventing the product rolling off the edge, and as they are carried around they are deflected inwardly by the paddles 32 which are 35 set at an angle as shown, and thence carried against the scraper blade 19 and directed into the discharge opening 10 in the center of the table, a suitable brace (not shown) is also provided for anchoring the members 19 40 and 33 in place.

The product discharging into the center openings are culls and half beans, and fall into the hollow shaft, thence discharging into the suitable receptacle placed beneath 45 it, it will also be obvious that a belt conveyor may be installed beneath this opening, or they may be discharged or spouted to a lower floor, also, by moving the brushes and scrapers around and setting them higher on 50 the table a cleaner picking can be effected.

As shown in Fig. 8 of the drawing these tables can be superimposed one above the other so that the capacity can be increased as desired.

From the foregoing description it will be 80 obvious that I have perfected a very simple, and inexpensive bean sorting machine, which will sort the product into several different grades.

What I claim is:—

1. A bean sorting machine comprising a 85 revolving flat tilted table having a plurality of small sand openings around the outer edge thereof, spaced apart brushes and scrapers thereon and stationary with relation thereto, a plurality of adjustable paddles for forcing the product towards the center of the table, and means for adjusting said paddles.

2. A bean sorting machine comprising a 90 revolving flat tilted table having a plurality of openings around its outer edge and provided with a discharge opening in the center thereof, spaced apart scrapers and brushes thereon and stationary with relation thereto, a plurality of adjustable paddles for forcing the product towards said discharge opening, manually operable means for adjusting said paddles, and means for revolving said table.

3. A bean sorting machine comprising a 95 revolving flat tilted table having a series of brushes and scrapers engaging the upper face thereof, and provided with a plurality of small openings around its outer edge, a 65 pair of spaced apart scrapers on the high side of the table and between which the product is fed, and a brush interposed therebetween for rolling the product, a pair of converging scrapers on the low side of the 70 table and disposed in angular relation to the first mentioned scrapers and adapted to separate the good beans from the dirt and cracked product, a second brush spaced from the first mentioned brush for rolling the 75 product and a plurality of adjustable paddles for forcing the product towards a discharge opening in the center of the table.

In testimony whereof I affix my signature.

LEE A. MEDCALF.
